UNITED STATES PATENT OFFICE.

FRANCESCO NUSCHAK, OF TRIESTE, ITALY.

ASTRONOMIC NAUTICAL APPARATUS.

Application filed August 2, 1922. Serial No. 579,255.

To all whom it may concern:

Be it known that I, FRANCESCO NUSCHAK, a subject of the King of Italy, and residing at 1 Via Donizetti, Trieste, Italy, have invented certain new and useful Improvements in Astronomic Nautical Apparatus, of which the following is a specification.

The invention relates to a device intended to determine the position of an observer on the surface of the earth or the line of position of the observer and it is based on the fact that any such point or line may be determined by means of the latitude of the observer, the hour angle of a star, the altitude of the star and its declination at the moment of the observation.

According to the invention, these four factors are reproduced on four arcs which represent respectively the prime meridian of the celestial sphere, a declination circle, the celestial equator and a vertical or azimuth circle. These four arcs are so combined and connected that their rotary movements are interdependent between them and they show automatically the value of any fourth factor when three factors are known or the variations of any unknown factor in dependence on the variations of a second unknown factor when two of these factors are known.

The device thus makes it possible to determine automatically the position of any point on the surface of the earth with the sole assistance of a chronometer, a sextant, the astronomic-naautical chart, the horizon of the sea or the artificial horizon, and without any of the astronomic-naautical calculations which have been necessary up to now.

The invention is shown, by way of example, in the annexed drawing wherein Figures 1 and 2 show a perspective view of two constructional forms of the invention.

The device shown in Figure 1 comprises four arcs 1, 2, 3 and 4. The arc 1 is arranged to rotate about the axis X—X' which passes through its center point at right angles to its plane. The arc 2 is adapted to rotate about its diameter P—P' which is parallel to the plane of the arc 1, and is further capable of rotating about the axis X—X' together with the arc 1 on which it is mounted. The arc 3 is firmly secured to the arc 1 in a plane which is perpendicular to the plane of the arc 1 and to

the axis P—P', and it may rotate about the axis X—X' together with the arcs 1 and 2. The arc 4 is rotatable around its diameter Z—Z' which is parallel to the plane of the arc 1.

These arcs are arranged so that the three arcs 2, 3, 4 have a common center O on the axis X—X' of the arc 1. They are intended to measure the angles formed by their planes and for this purpose are provided with graduations and with a vernier 5, 6, 7 and 8 respectively to take the readings. The verniers 6 and 8 of the arcs 2 and 4 are connected by a pin 9 on which they may rotate about the axis Y—Y' which passes through the center O. In this way, an interdependence is created between the movements of the arc 4 and those of the other arcs.

The arc 1 is rotatably mounted on a support 10 which has also pivotally secured to it the arc 4 and the arcs 2 and 4 are counterweighted as shown in 11 and 12 to balance the device.

The arc 1 represents the prime meridian of the celestial sphere and is graduated to show the latitudes. The arc 2 represents a declination circle and is graduated so as to show the declinations of the stars. The arc 3 represents the celestial equator and is graduated to show the hour angles of the stars. The arc 4 represents a vertical circle and is graduated to show the altitudes of the stars. The combination of these four arcs reproduces a quarter of the celestial vault, which is quite sufficient to solve all the combinations of the stars above the horizon of an observer, considering that eastward and westward of the prime meridian there appear the same combinations of arcs and therefore the same results, except that the hour angle must be substracted from 24 hours when it is to the east of the meridian.

Considering now that for determining the position of a point of observation on the surface of the earth it is necessary to have recourse to the following four factors, latitude of the observer, hour angle of a star, the altitude of the star and its declination at the moment of observation, it is evident that when three of these factors are known and the verniers of the respective arcs are set in accordance with these factors, the device will automatically show the fourth factor and thus the position of the observer will be ascertained. Or when two factors are known the device will show the variations

of the third factor in dependence on the variations of the fourth factor. When it is desired to determine the line of position of the observer it will be understood that when 5 setting the device, for example in accordance with the declination and the altitude of the star, it will show for different latitudes different hour angles and therefore different longitudes and on the Mercator map 10 these points will be the points of the line of position of the observer at the moment of the observation. A line perpendicular to this line will be the azimuth of the star.

When two observations of stars made at 15 the same moment and on the same side of the prime meridian are available the device shown in Figure 2 may be employed wherein the three arcs 2, 3 and 4 have each a double indicated respectively by 2^a, 3^a and 4^a. 20 In this case, when the distance between the two arcs 2 and 2^a is set to be equal to the difference of the right ascensions of the stars and the arc 2 is set in accordance with the declination of one star and the arc 2^a in accordance with the declination of the second star and the arcs 4 and 4^a are set in accordance with the respective altitudes, it is possible to obtain immediately the latitude and the hour angle of a star and thereby the longitude of an observer at the moment of observation. If the two stars are one on the one side and the other on the other side of the prime meridian, the two declinations and the two altitudes are used as above to adjust 25 just the device and the arcs both of the hour angle and of the latitude are rotated until the sum of the two hour angles is equal to the difference of the right ascensions of the two stars; the latitude indicated by the de-

vice will then be the latitude of the observer 40 and the longitude will be found by aid of the hour angle.

What I claim is:

1. A device for determining the position of a point of observation or the line of position of the observer on the surface of the earth, comprising, four graduated arcs representing, respectively, the celestial meridian, the declination circle, the celestial equator, and a vertical circle, each of which arcs is constructed to be set by rotation on an axis, the arc representing the meridian and that representing the celestial equator, being rigidly connected together and rotatable about a vertical axis, a horizontal polar axis on the meridian arc, the arc representing the declination circle being rotatable about the horizontal polar axis, and the arc of the vertical circle being rotatable about a horizontal axis, these three axes intersecting in a common center point above the plane of the meridian arc. 50

2. A device as in claim 1, wherein the arcs representing respectively the declination circle, the celestial equator and the vertical circle are each duplicated in order to allow of determining, from observations of two stars, the geographical latitude and the hour angle of the point of observation. 60

In testimony whereof I have signed at 70 Trieste, in the Kingdom of Italy, this 10th day of July, 1922, in the presence of two subscribing witnesses.

F. NUSCHAK.
